UNITED STATES PATENT OFFICE.

FREDRICK C. MILLER, OF NEWPORT, KENTUCKY.

CIGAR-MOLD.

SPECIFICATION forming part of Letters Patent No. 329,196, dated October 27, 1885.

Application filed November 3, 1884. Serial No. 147,126. (Model.)

To all whom it may concern:

Be it known that I, FREDRICK C. MILLER, a citizen of the United States, residing at Newport, in the county of Campbell and State of Kentucky, have invented certain new and useful Improvements in Cigar-Molds, of which the following is a specification.

My invention relates to those cigar-molds which are provided with lower members divided longitudinally transverse of the cups into body and end portions and mounted upon bases to which the end portions are permanently secured and the body portions movably secured to elevate the fillers from the end portions.

My invention also relates to those cigar-molds in which the upper members are raised from one end to remove them from their lower members.

As heretofore constructed, it has been the custom to form the first-named molds with a lower member provided with a base having a longitudinal and vertical back piece, the body portion of the lower member being hinged to the upper inner corner of the back piece, thus occupying the space and seating between the back piece and end portion. There are disadvantages arising from this construction which my invention overcomes. Where the back piece is employed, it closes the rear ends of the cups in the lower member. The body portion is liable to wedge or get fixed between it and the end portion, and the fillers cannot extend beyond the ends of the cups contiguous to the back piece, as customary in other molds. In the other form of mold referred to I have found that the working of the lever to open the mold endwise has rapidly destroyed the upper member by cutting into and splitting it.

In my present invention I have combined with such end-opening molds a provision to prevent this rapid destruction, and which effectually overcomes the present only objection to such molds.

My improvement consists, first, in a mold in which the longitudinal and vertical back piece of the stationary base is dispensed with, and the body portion of the lower member is secured movably at the bottom directly to the base. This construction lightens the weight of the mold, permits the use of a vertical di-

vision between the body and end portions of the lower member, permits the fillers to extend beyond the cups, as formerly, and has nothing to interfere with the ready removal of the body portion.

My improvement consists, further, in applying a metallic wear-plate to the under side of the lid of the upper member, or at a corresponding point on the lower member, or at both places, to receive the lever employed to pry open a mold which is separated endwise after the fillers are pressed.

In order that my invention may be more fully understood, I will proceed to describe it with reference to the accompanying drawings, in which—

Figure I is a plan view of the two members separated. Fig. II is a perspective view of one end of the mold. Fig. III is a transverse section of the same, showing the body portion hinged to the base and raised to permit the manipulation or withdrawal of the fillers by their tips.

1 represents the base of the mold, on which is mounted the hard-wood end or tip portion, 2, of the lower member, in which are formed the cavities for the points of the fillers or bunches. The hard-wood blocks 3, in which are formed the cavities for the butt-ends of the fillers or bunches, are mounted upon a thin backing, 4, connected by hinges 5 to the side of the base 1. The blocks and thin backing form the body portion of the lower member. Recesses 6 for the forefingers are formed in the ends of the lower portion of the mold. This construction is such that after the fillers or bunches have been pressed and the upper member removed the hinged body portion 3 of the lower member may be raised on or elevated from the base by placing the thumbs upon the ends 7 of the end portion, 2, and the forefingers in the recesses 6 provided therefor in the ends of the lower portion of the mold. When raised into the position shown in Fig. III, the cigar fillers or bunches can be easily removed from their cavities without liability to breakage. In other respects the mold may be used in the same manner as those ordinarily in use, the advantage over the ordinary molds being in the capacity for more rapid and safe removal of the fillers from their cavities.

No springs or catches need be employed to hold the two parts of the lower member together. The dowel-pins 8 are fixed in the movable body portion 3 4 of the lower member, and are made of sufficient length to engage not only with the lid of the upper member, but with the base 1 of the mold beneath the body portion 3 4 of the lower member. All parts are thus held in perfect contact with each other, so much so that if need be the hinges for fixing the body portion and base together may be dispensed with.

At the end of the upper member or lid, to which the force necessary for holding down the body portion to its seat and separating the upper member from the lower member is applied endwise, I have fixed an iron or other metallic plate, 9, to serve as a protection against wear of that part of the member or lid. When the mold is filled with tobacco and tightly pressed, the two members are apt to become closely wedged together, so as to necessitate the use of an opening-lever inserted between the ends of the two members. Such a lever rapidly wears out the lid of the mold unless a protector, such as I have devised and described above, is applied. A plate may also be fixed to the end of the lower member immediately under the upper one, although the wear at this point is much less than at the lid.

Having thus described my invention, the following is what I claim as new therein and desire to secure by Letters Patent:

1. A cigar-mold consisting of a base, end 35 portion secured permanently to the base, body portion secured at the bottom to the top of the base and removable therefrom, and an upper member, substantially as set forth.

2. A cigar-mold consisting of a base, end 40 portion secured permanently to the base, body portion 3 4, hinged at the bottom directly to the rear upper corner of the base, and an upper member, substantially as set forth.

3. A cigar-mold consisting of base 1, end 45 portion, 2, secured permanently to the base, body portion 3 4, secured movably to the base, upper member, and dowel-pins 8, secured to the body portion, and by which the base and upper members are engaged with the body 50 portion, substantially as set forth.

4. A cigar-mold consisting of a base, 1, and movable body portion 3 4, having forefinger-recesses 6 at the ends thereof, end portion, 2, permanently secured to the base and having 55 thumb-recesses 7, and an upper member, substantially as set forth.

5. A cigar-mold consisting of a base, 1, end portion, body portion 3 4, and upper member having a metal plate, 9, at the opening end of 50 the mold, the body portion and end portion being recessed to admit a lever for opening the mold endwise, substantially as shown and described.
